[57] CLAIM

The ornamental design for a replaceable blade broadhead arrow tip, as shown.

DESCRIPTION

FIG. 1 is a perspective view of a first embodiment of a replaceable blade broadhead arrow tip showing my new design;

FIG. 2 is a top plan view of the first embodiment;

FIG. 3 is a bottom plan view of the first embodiment;

FIG. 4 is a rear elevational view of the first embodiment;

FIG. 5 is a front elevational view of the first embodiment;

FIG. 6 is a perspective view of a second embodiment of the replaceable blade broadhead arrow tip showing my new design;

FIG. 7 is a top plan view of the second embodiment;

FIG. 8 is a front elevational view of the second embodiment; and

FIG. 9 is a rear elevational view of the second embodiment.
